(57) **CLAIM**

The ornamental design for a multi-function sanitation cabinet, as shown and described.

DESCRIPTION

FIG. 1 is a perspective view of a multi-function sanitation cabinet, the dashed lines showing optional features and forming no part of the claimed invention;

FIG. 2 is a side elevational view, the opposite side being a mirror image of the side shown;

FIG. 3 is a top plan view;

FIG. 4 is a front elevational view;

FIG. 5 is a rear elevational view; and,

FIG. 6 is a bottom plan view.
